SPECTACLE-MOUNTED EYESHADE

Herman Zuckerman, Hollywood, Calif.

Application June 29, 1953, Serial No. 25,720

Term of patent 7 years

(Cl. D57—1)

To all whom it may concern:

Be it known that I, Herman Zuckerman, a citizen of the United States, residing in Hollywood, in the county of Los Angeles and State of California, have invented a new, original, and ornamental Design for a Spectacle-Mounted Eye Shade, of which the following is a specification, reference being had to the accompanying drawing, forming part thereof.

Fig. 1 is a front elevational view of a spectacle-mounted eye shade, showing my new design.

Fig. 2 is a side elevational view thereof.

Fig. 3 is an enlarged plan view.

Fig. 4 is a perspective view.

I claim:

The ornamental design for a spectacle-mounted eye shade, substantially as shown.
